BUCKET EXCAVATOR AND LOADER

Charles W. Shippee, Worcester, Mass.

Application December 1, 1932, Serial No. 645,269

5 Claims. (Cl. 37—4)

This invention relates to a machine of the bucket type by which loam, dirt or other material may be economically excavated and loaded.

It is the general object of my invention to provide a machine for such purposes in which improved means for raising and dumping an excavator bucket is provided, together with improved devices for conveniently controlling the operation thereof.

10 My invention further relates to arrangements and combinations of parts which will be herein-after described and more particularly pointed out in the appended claims.

A preferred form of the invention is shown in 15 the drawings, in which

Fig. 1 is a side elevation of my improved excavator and loader;

Fig. 2 is a plan view thereof;

20 Fig. 3 is a detail sectional side elevation, taken along the line 3—3 in Fig. 2;

Fig. 4 is a detail sectional elevation, taken along the line 4—4 in Fig. 2 and looking in the direction of the arrow 4 in Fig. 3, and

25 Fig. 5 is a rear elevation of certain parts, looking in the direction of the arrow 5 in Fig. 4.

Referring to the drawings, I have shown an excavator and loader of the bucket type and comprising a frame 10 mounted on steering wheels 11 and driving wheels 12. An engine E is connected 30 through the usual clutch and transmission mechanism to a cross shaft 14 having sprockets 15 connected by chains 16 to sprockets 17 (Fig. 2) secured to the driving wheels 12. The engine E is thus effective to drive the wheels 12 in either desired direction.

35 A body or hopper B is mounted on a rearward extension of the frame 10 and is provided with gates 20 connected by links 21. Cords or cables 22 are disposed at the two opposite sides of the machine, and one end of each cable 22 is secured to one of the links 21 while the other end of each cable 22 is secured to a separate winding drum 23 on a cross shaft 24 mounted in fixed bearings 25 (Fig. 1) extending upwardly from the frame 10.

40 A worm wheel 26 on the cross shaft 24 is engaged by a worm 27 also mounted in fixed bearings and provided with a handle 28. By turning the handle 28 in one direction or the other, the links 21 may be raised or lowered and the gates 20 45 may be correspondingly closed or opened, as indicated in full and dotted lines respectively in Fig. 1.

45 The handle 28 is conveniently positioned adjacent a seat S from which also the steering wheel

29 and the drive wheel control devices may be conveniently operated.

A bucket 30 is provided with rolls or trunnions 31 positioned in channeled guideways 32 rigidly mounted on the frame 10. Each guideway 32 5 preferably comprises an upright intermediate section, a segmental upper section and a short downwardly and rearwardly inclined lower section.

As the bucket 30 is raised by mechanism to be described, it is guided from the full line excavating position shown in Fig. 1 to the dotted line dumping position in the same figure. The substantial inversion of the bucket is effected by the action of the guideways 32 on the trunnions 31.

10 For raising and lowering the bucket 30, I provide cables 40 at each side of the machine. Each cable 40 makes several turns around a separate winding drum 41 on a winding shaft 42. One end of each cable 40 passes over a guide-pulley 44 (Fig. 1) and around a second guide-pulley 45 15 and is secured to a stud 46 in the bucket 30. The other end of each cable 40 passes around guide-pulleys 50, 51, 52 and 53 and is also secured to the stud 46.

20 The guide-pulleys 45, 51, 52 and 53 are mounted 25 on brackets secured to the guide-ways 32, while the guide-pulleys 44 and 50 are mounted on brackets secured to the frame 10 or to the body B.

The winding shaft 42 is connected by sprockets 60 and 61 (Fig. 1) and a chain 62 to a reversing 30 clutch mechanism M having a drive shaft 65 (Fig. 2) connected by a chain and sprocket drive to the crank-shaft of the engine E. A clutch shaft 70 (Fig. 2) in the mechanism M is connected by an arm 71 and link 72 to a control lever 35 73 (Fig. 1) pivoted at 74 and conveniently adjacent the seat S.

40 The details of construction of the transmission mechanism M are not shown herein as this mechanism constitutes no part of my invention and any suitable reversing gear and clutch mechanism may be used. It is sufficient for the purposes of this application to state that when the lever 73 is displaced from neutral upright position in the direction of the arrow a in Fig. 3, the winding 45 shaft 42 will be rotated in one direction and when the lever 73 is displaced in the direction of the arrow b, the winding shaft 42 will be rotated in the opposite direction.

45 Referring to Fig. 1, it will be seen that rotation of the winding shaft 42 in a clockwise direction will wind up the lower run of each cable 40, thus pulling the bucket 40 downward a desired distance and into the material to be excavated. Rotation of the winding shaft 42 in the opposite 50 55

or anti-clockwise direction will wind up the upper run of each cable 40, thus lifting the bucket 30 and moving it along the vertical and segmental guideways 32 to the dumping position shown in 5 dotted lines in Fig. 1.

It should be noted that the short downwardly and rearwardly inclined lower section of the guide-ways 32 cause the bucket to present its front or excavating edge to the material to be 10 excavated, and that as soon as the bucket begins to rise, this front edge is also elevated to prevent displacement of the material in the bucket.

Provision is also made for locking the winding shaft 42, so as to hold the bucket 30 in any 15 desired position. For this purpose I provide a brake drum 80 (Fig. 3) on the shaft 42 and I provide a brake-shoe 81 mounted on a plunger 82 vertically slideable in bearings 83 and yieldingly pressed downward against the drum 80 by 20 a heavy coil spring 84 engaging a collar 85 on the plunger 82.

An arm 87 (Figs. 3 to 5) is secured to the upper end of the plunger 82 and projects over a pair of rolls 88 mounted in spaced relation on a lever 90 25 rocking on a fixed pivot 91 and connected by a link 92 to a downward extension of the lever 73 previously described.

When the lever 73 and rocking lever 90 are in 30 midposition, the rolls 88 are clear of the overlying arm 87 and the brake-shoe 81 is forced against the brake-drum 80 by the coil spring 84, thus holding the winding shaft 42 from rotation. As soon as the lever 73 is displaced from mid or 35 neutral position in either direction, the lever 90 is also displaced and one of the rolls 88 engages the arm 87 and raises the brake-shoe 81 from the drum 80, permitting free rotation of the winding shaft 42.

I thus control the raising and lowering of the 40 bucket 30 and the locking of the bucket in any desired position by manipulation of the single lever 73.

My improved excavator and loader is of such 45 construction that the bucket may be lowered and maintained at a desired depth and may be quickly and easily raised and dumped into the body or hopper B as soon as the bucket is filled. While I have shown and described a self-contained machine adapted to itself transport and dump the 50 loaded material, it is obvious that the body B may be omitted and that the excavated material may be dumped directly into a trailer or other separately mounted container.

Having thus described my invention and the 55 advantages thereof, I do not wish to be limited to the details herein disclosed, otherwise than as set forth in the claims, but what I claim is:—

1. An excavator and loader comprising a motor vehicle having a frame, an excavator bucket, 60 guideways for said bucket supported on said frame, and means to move said bucket in said guideways between a lowered loading position and a raised and inverted dumping position, said latter means comprising cables secured to said bucket, guide rolls for said cables, and power 65 means to move said cables in both directions and to thereby positively raise said bucket to inverted dumping position and positively return

said bucket to lowered excavating position and positively hold said bucket in said latter position.

2. An excavator and loader comprising a motor vehicle having a frame, an excavator bucket, 5 guideways for said bucket supported on said frame, and means to move said bucket in said guideways from a lowered loading position to a raised and inverted dumping position, said buckets being open at the front and top when in excavating position and having portions cooperating with said guideways to tilt said bucket backward to retain its load as the bucket starts to rise and to thereafter invert said bucket to dump the load substantially at its elevated rearward limit of travel, said bucket moving means acting 10 positively in both directions and positively holding said bucket in lowered excavating position.

3. An excavator and loader comprising a motor vehicle having a frame, an excavator bucket, guideways for said bucket supported on said frame, and means to move said bucket in said guideways from a lowered loading position to a raised and inverted dumping position, said latter means comprising cables secured to said bucket, guide rolls for said cables, and power means 15 to move said cables in both directions to positively raise and positively lower said bucket, said bucket having portions engaging said guideways at two spaced points on each side of said bucket and being attached to said cables at a third point 30 on each side of said bucket substantially spaced above the center line of said spaced points and positioned between said points.

4. An excavator and loader comprising a motor vehicle having a frame, an excavator bucket, 35 guideways for said bucket supported on said frame, and means to move said bucket in said guideways from a lowered loading position to a raised and inverted dumping position, said latter means comprising cables secured to said 40 bucket and forming endless operating elements for said bucket and having intermediate portions remote from said bucket, guide rolls for said cables, winding drums about which said intermediate portions of said cables are wrapped, and 45 means to rotate said drums in either selected direction to positively raise or positively lower said bucket.

5. An excavator and loader comprising a motor vehicle having a frame, an excavator bucket, 50 guideways for said bucket supported on said frame, means to move said bucket in said guideways from a lowered loading position to a raised and inverted dumping position, said buckets being open at the front and top when in excavating position and having portions cooperating with said guideways to tilt said bucket backward to retain its load as the bucket starts to rise and to thereafter invert said bucket to dump the load substantially at its elevated rearward limit of travel, said bucket moving means acting 55 positively in both directions and positively holding said bucket in lowered excavating position, and a single manually operated member effective to control and determine the operation of said bucket moving and holding means.

CHARLES W. SHIPPEE.
